UNITED STATES PATENT OFFICE.

BERTRAM JOSEPH DYKES, OF GLEADLESS, NEAR SHEFFIELD, ENGLAND.

CALENDERING OR IRONING MACHINE.

Application filed December 5, 1923, Serial No. 678,716, and in Great Britain December 12, 1922.

This my invention has for its object improvements in the means of calendering or ironing wool fabrics and the like, and in folding and baling the same, more particularly those of a tubular form knit in a continuous length, so that the fabric has its longitudinal wales or threads quite straight corresponding with the edges of the fabric, and the horizontal courses or threads also straight and at right angles to the edges, all in such a manner that the fabric passes into and through the machine to the folding or baling appliances without deformation of the longitudinal wales and horizontal courses.

To attain this end, the machine has two vertical housings suitably fixed one at each side of the base-plate, and the housings are formed to carry two or preferably three pairs of calendering cylinders, as well as two or more pairs of auxiliary guide rollers for guiding the fabric in a proper form to the calendering cylinders.

All the calendering cylinders are driven by suitable gearing from a driving shaft which is actuated by an electric motor, or by belting or other suitable means.

One calendering cylinder of each pair has its shaft rotating at each end in suitable bearings which are stationary in the housings, and the other cylinder of each pair has its shaft turning in bearings which can be adjusted horizontally in the housings by suitable screws, gearing and handwheel to each, all in such a manner that the fabric may pass through the calendering cylinders under a desired pressure. The shafts of the calendering cylinders at one side of the machine are of such a length that gear wheels with specially long teeth may be fixed thereon, so as to always ensure being properly geared to each other when the movable bearings are moved inwards or outwards.

The calendering cylinders and their shafts are formed hollow, so that the cylinders can be heated by steam, gas, or other suitable means.

At the top of the machine is a suitably driven roller, over which the fabric passes into the machine over an expanding gauge, and over which the fabric is guided by several pairs of vertical and horizontal guide rollers, all positively driven by gearing or other suitable means from the driving shaft. These guide rollers serve the purpose of assisting the fabric to pass between the calendering cylinders in the lower part of the

machine without deformation of the fabric as named above. The carriages carrying these guide rollers can be adjusted on the driving shafts to suit the varying widths of the fabric passing between them.

After passing through the top pair of calendering cylinders, the fabric passes over a second expandible gauge which can also be adjusted to any desired width, and in some cases may be fitted with guide rollers positively driven by gearing from the driving shaft in a like manner to the upper gauge. From thence the fabric passes downwards and through or between one or more other pairs of calendering cylinders—all in such a manner that the fabric passes through all these cylinders without deformation of the threads as named above, and at the same time giving the required ironing surface thereto.

After leaving the calendering cylinders the fabric is baled, or wound upon a horizontal roller at the base of the machine, and suitably driven therefrom. Or in some cases it may be delivered in a folded state by suitable oscillating mechanism actuated by the machine.

The calendering cylinders may in some cases be covered with a preparation to improve the ironing of the fabric passing through them.

Also, when the machine is driven by belting, electric motor or the like, a suitable friction clutch may be fitted on the driving gear so that the operator may have perfect control of the machine.

I attain these objects by the mechanism illustrated in the accompanying drawings, in which:—

Fig. 1 is a front elevation of my improved calendering and baling machine.

Figure 2 is an end elevation of the same machine, when looking at the right hand side as shown on Figure 1.

Figure 3 is a plan of the same machine.

Figure 4 is a front elevation of the top expandible gauge and carrying carriages.

Figure 5 is an end elevation of the same gauge when looking at the right hand side as shown on Figure 4.

Figure 6 is a plan of the same gauge.

Figure 7 is a front elevation of the second or lower gauge.

Figure 8 is an end elevation of the same gauge when looking at the right hand side as shown on Figure 7.

Fig. 9 is a vertical section on broken line 9—9 Fig. 1, showing the position of worm wheel casing E' in dot and dash lines and Fig. 10 is a vertical section on line 10—10 Fig. 1.

Similar letters of reference refer to similar parts throughout the several views.

In these views A, A represents the vertical 10 housings each fixed one at each side of the baseplate B, the three pairs of calendering cylinders are represented by C, C, and the four pairs of auxiliary guide rollers by D, D, these are for guiding the fabric in a suitable form to the calendering cylinders C, C.

15 The calendering cylinders C, C are driven by gearings G, G from the driving shaft G2 actuated—through a worm wheel and worm (not shown) in casing E1—by the electric motor E, or by any other suitable driving 20 means.

The hollow shafts—one of each pair—of the calendering cylinders C, C rotate at each 25 end in stationary bearings F, F fixed on the housings A, A, and the shafts of the other cylinder of each pair turn in sliding bearings F1, which can be adjusted horizontally by screws having spring cushions by the handwheels H, H through the bevel gearing H1, so that any desired pressure may be 30 brought to bear on the fabric passing between the calendering cylinders C, C. Gear 35 wheels G1 with specially long teeth are fixed on the calendering cylinder shafts at one side, so as to ensure the gear wheels G, G always being properly geared into each other when the bearings F1 are moved to and fro.

The calendering cylinders C, C are heated by steam or other suitable means passing 40 through the pipes J, J, and the stuffing boxes J1 on the hollow shafts of the calendering cylinders, and thence through these cylinders and out by the outlet pipes J2.

The fabric is first passed over the roller 45 D1, and thence over the roller D¹¹ at the top of the machine to the upper expandible gauge K over which it passes without deformation of the fabric through the top pair of calendering cylinders C, then to the second or lower expandible gauge K1, passing 50 over same—without deformation—and thence between the second and third pairs of calendering cylinders C, C to the baling roller M suitably driven from the machine, or to a folding appliance as desired. The 55 folding appliance is shown by N, which consists of arms N, N pivoted from the machine at N1 and fitted with guide rollers T, T for

the easy passing of the fabric thereon as the arms are oscillated backwards and forwards by the bar O from the machine. The baling 60 roller M, and the guide rollers T, T of the folding appliance are preferably driven from the machine by belt or gearing as shown on the drawings.

The top expandible gauge K is expanded 65 or contracted at will on the guide bars L, L, and the two halves are held in place by the ratchet and pawl L1. The gauge K is carried between the carriages P, P, which are fitted with the rollers R, R driven in a positive manner by the gearing S, S from the driving shaft Q1, which has a keyway formed therein the full length between the bearings in the housings for actuating the bevel gear wheels S1 sliding thereon. The 70 gauge carriages are carried on the guide bars Q, Q, and the two halves of the expandible gauge K are adjusted to any desired width by the right and left hand screw bar U and hand spoke wheel U1. 75

The second or lower expandible gauge K1 is also expanded or contracted at will and by hand on the guide bars L, L and in the same manner as the gauge K, the two halves being held in position by the ratchet and pawl L1. Friction rollers V, V are fitted 80 on the halves of the expandible gauges to assist the passage of the fabric more easily over the same.

What I do claim as my invention, and 85 desire to secure by Letters Patent, is:—

1. In a calendering machine, in combination, pairs of superimposed calendering cylinders, housings, bearings on said housings for said cylinders, expandible gauges arranged one above the other, adjustable carriages carrying the uppermost gauge, and positively driven guide rollers on the carriages for the purpose substantially as herein 90 described.

2. In a calendering machine, the combination of expandible gauges for insertion into tubular material, carriages provided with positively driven guide rollers, one of said gauges being supported by said carriages, pairs of superimposed calendering cylinders, shafts for said cylinders, bearings for said shafts, and housings on which said bearings are provided substantially for the purpose specified.

100 In testimony whereof I have signed my name to this specification.

BERTRAM JOSEPH DYKES.
